(57) **CLAIM**

The ornamental design for a bottle, as shown and described.

DESCRIPTION

FIG. 1 is a top, right, frontal perspective view of a bottle showing my new design, the rounded shoulder portion of the bottle being transparent;

FIG. 2 is a front elevational view of the bottle of FIG. 1; FIG. 3 is a right elevational view of the bottle of FIG. 1; FIG. 4 is a left elevational view of the bottle of FIG. 1; FIG. 5 is a top plan view of the bottle of FIG. 1; and FIG. 6 is a rear elevational view of the bottle of FIG. 1.

FIG. 7 is a top, right, frontal perspective view of a bottle showing another embodiment of my new design, the rounded shoulder portion not being transparent;

FIG. 8 is a front elevational view of the bottle of FIG. 7; FIG. 9 is a right elevational view of the bottle of FIG. 7; FIG. 10 is a left elevational view of the bottle of FIG. 7; FIG. 11 is a top plan view of the bottle of FIG. 7; and, FIG. 12 is a rear elevational view of the bottle of FIG. 7.
